UNITED STATES PATENT OFFICE.

MORGAN H. SLY AND PLEASANT F. WOOD, OF ADRIAN, MISSOURI; SAID SLY
ASSIGNOR TO SAID WOOD.

FOLDING WASH-BENCH.

SPECIFICATION forming part of Letters Patent No. 352,369, dated November 9, 1886.

Application filed October 29, 1885. Serial No. 181,314. (No model.)

To all whom it may concern:

Be it known that we, MORGAN H. SLY and PLEASANT F. WOOD, citizens of the United States, residing at the city of Adrian, in the 5 county of Bates and State of Missouri, have invented certain new and useful Improvements in Folding Wash-Benches, of which the following is a specification, reference being had therein to the accompanying drawings.

10 This invention relates to certain improvements in folding wash-benches; and it has for its objects to provide a folding supporting-frame for the tub, which will also carry the washing machinery proper, the parts being so 15 arranged that the frame may be readily set up for use or folded into a compact form for storage or transportation, as more fully hereinafter specified, and particularly pointed out in the claims. These objects we attain by the means 20 illustrated in the accompanying drawings, in which—

Figure 1 represents a perspective view of our improved apparatus, showing the frame in position to support the tub and the washing machinery in proper position for operation, the tub being omitted. Fig. 2 represents a longitudinal vertical sectional view of the washing-machine proper. Fig. 3 represents a longitudinal sectional view of the apparatus, showing 25 the same folded for transportation or storage. Fig. 4 represents a detached view showing one of the stops by which the lower portion of the frame is held when in position for supporting the tub, and Fig. 5 a detached view 30 showing the locking devices for holding the frame when folded.

The letter A indicates two standards, which are in a vertical position when the frame is arranged for operation. Near the lower ends of 40 said standards are pivoted, by means of a round, B, two beams, C, which extend obliquely forward, as shown in Fig. 1, when the frame is set up. The forward ends of said beams are connected by a round, D, and at an intermediate point are pivoted the beams E by means 45 of a round, F, the said beams setting obliquely, and forming the forward legs of the frame when set up. The lower ends of said beams E are connected by a round, G, which braces the 50 parts. To the oblique beams C are secured the

metallic stops H, against which the forward edges of the beams E rest when the frame is elevated, so as to keep it in such position.

The letter I indicates two beams, which form a horizontal support for the tub when the frame is set up. The said beams I are pivoted at their rear ends on the transverse beam or round L, connecting the two standards A, and at their forward ends they are provided with hooks or notches a, which are adapted to set 55 over the round D when the device is set up for use. These beams I are provided with a bracing-round, N, near their forward ends.

Between the upper ends of the standards A are pivoted, by means of a round, P, the swinging beams R, which are connected at their upper ends by a round, S. The lower or forward ends of said beams are beveled, and have secured to them a transverse flat board, T, which supports the washing machinery proper, and 60 which sets in the upper part of the tub when the apparatus is arranged for operation. To the said board are secured two standards, U, which are slotted, as indicated by the letter V, 65 for the reception of the shaft of the upper corrugated roller, W, forming part of the washing mechanism. The said shaft is held to its bearings with a yielding pressure by means of the eyebolts A', which extend through apertures in the board, and through openings in a leaf-spring attached thereto by means of the nuts B', which set over the screw-threaded ends of 70 said bolts.

The letters C' D' respectively indicate corrugated and plain rollers, which extend longitudinally between the standards in close proximity to the main corrugated roller, as shown 75 plainly in Figs. 1, 2, and 3 of the drawings. The shaft of the main roller at one end is provided with a crank, R', by which it may be 80 turned.

The ends of the board T are rounded, and are provided with segments F', which are slotted at one end and pivoted to the board at the other. Through the slotted ends pass the bolts G', 85 which have binding-nuts, by means of which the segments may be set so as to project more or less over the ends of the board, so as to adjust and adapt it to fit tubs of different diameters.

The letters H' I' indicate two reversely-set hooks or clamps, which are pivoted to the rounds L, and adapted to lock and hold the frame together when folded for transportation or storage.

As the washing machinery proper, located upon the flat board T, attached to the forward ends of the swinging beams R, is not claimed in this application, we reserve the right to 10 make a new application therefor.

The operation of our invention will be readily understood in connection with the above description. When required for use, the frame is set up, as shown in Fig. 1, the tub placed 15 upon the horizontal platform, and the washing machinery properly secured therein, when the machine is ready for operation. When not in use, the parts are folded together, as shown in Fig. 3 of the drawings, being locked or 20 clamped by means of the hooks described.

Having thus described our invention, what we claim, and desire to secure by Letters Patent, is—

1. The combination, with the standards A, 25 connected together by suitable rounds, of the

oblique beams C, pivoted to the said standards A, connected together at their forward ends by a round, D, and provided with stops H, the beams or legs E, pivoted to the oblique beams C, and the horizontal pivoted beams I, 30 with hooked ends, substantially as described.

2. The combination, with the standards A, connected together, of the oblique beams C, pivoted to the said standards A and connected together at their forward ends by a round, D, 35 the stops H, secured to the beams C, supporting-beams E, pivoted to beams C, the pivoted beams I, with hooked ends, and the swinging beams R, pivoted to the upper ends of the standards A and adapted to support the washing mechanism, all arranged substantially as described.

In testimony whereof we affix our signatures in presence of two witnesses.

MORGAN H. SLY.
PLEASANT F. WOOD.
